FOIL PACKAGING TRAY

David T. Dittman, Atlanta, Ga., assignor to Pet,
Incorporated, St. Louis, Mo.

Filed Apr. 3, 1968, Ser. No. 11,287

Term of patent 14 years

Int. Cl. D9—03

U.S. Cl. D9—219

Fig. 1

Fig. 2

Fig. 3

FIG. 1 is a front-side-top perspective view of a foil packaging tray embodying my new design;

FIG. 2 is a front-side-bottom perspective view of the foil packaging tray shown in FIG. 1; and,

FIG. 3 is a top plan view of the foil packaging tray shown in FIG. 1. The rear and side not shown are similar to the front and side shown.

I claim:

The ornamental design for a foil packaging tray, substantially as shown and described.
